UNITED STATES PATENT OFFICE.

ARTHUR J. RAY, OF CHICAGO, ILLINOIS, ASSIGNOR TO AUTOMATIC ELECTRIC, INC., OF CHICAGO, ILLINOIS, A CORPORATION OF DELAWARE.

MULTIOFFICE AUTOMATIC TELEPHONE SYSTEM.

Application filed February 2, 1923, Serial No. 616,476. Renewed December 13, 1926.

The present invention relates in general to automatic telephone systems of the multi-office type, but is more particularly concerned with systems of this character in which the main offices of the system have smaller exchanges subsidiary to them, the latter being commonly known as sub or satellite exchanges; and the object of the invention is to provide a new and improved method of completing connections between adjacent sub exchanges as well as local sub exchange connections, the sub-exchange to main-exchange and the main-exchange to sub-exchange trunk lines not being used for such connections, the whole to be accomplished without departing from or in any way modifying the standard numbering arrangement.

In Patent No. 1,542,958, issued June 23, 1925, to A. J. Ray, a switching selector repeater is illustrated and described which is capable of completing local sub-exchange connections without utilizing sub to main-exchange or main-exchange to sub-exchange trunk lines. A switching selector repeater, as described in the above mentioned application, ordinarily operates in a sub office in which at least the first two digits of all numbers are the same, but when it is required to switch from the banks of the switching selector repeater to another sub office, the switching selector repeater may be required to switch on two entirely different combinations of digits. When this is the case it is necessary to provide means to prevent combinations of digits out of the switching combinations from causing the switching selector repeater to cut off the main exchange trunk. For example, if the local switching combination is 914, while the switching combination for an adjacent sub exchange is 763, the switching selector repeater must not switch on 913 and 764, as these combinations represent trunk connections through the main office.

More specifically, one of the principal objects of the present invention is to provide the means above referred to, the said means preventing the switching of the switching selector repeater on any combination of figures except those designating the local sub exchange or an adjacent sub exchange.

There are other objects of the invention not now specifically mentioned which, to-

gether with those referred to above, will be described more fully hereinafter.

Although the invention is applicable to systems of different sizes, it will be assumed for convenience that we are dealing with a system that has an ultimate capacity of 100,000 lines. It will be assumed further that there are a number of main offices, of 10,000 lines each, and that certain of these offices each have an associated sub exchange of 100 lines. It will also be assumed that the geographical location of certain of these sub exchanges is such that it is desirable to complete calls from one to the other directly, rather than by the customary routing from first sub to first exchange, to second exchange to second sub. In a 100,000 line system the first digit dialed determines to which group of 10,000 lines the call is going. The second digit determines to which group of 1,000, while the third digit determines the particular group of 100 lines for which the call is intended. Now since each sub exchange has only 100 lines in it and the third digit dialed picks out the hundreds group, we must have in the sub offices switching selector repeaters capable of switching on the third digit.

The general trunking arrangement is not novel and consequently is not shown, the drawings showing only such of the equipment as will be used to explain the novel features of the invention. Figs. 1, 2, 3, and 4 show by means of the usual circuit diagram the apparatus required to enable the subscriber at substation A (Fig. 1) in a sub exchange to extend local calls, to extend a call to station A' in the main exchange, or to extend calls to other sub exchanges. Fig. 4, more specifically, shows the arrangement of the wiring in the banks of the switching selector repeater in the sub exchange.

Fig. 5 is a layout showing how sheets 1 to 4, inclusive, should be joined together.

The substation A shown in Fig. 1 and the substation A', Fig. 3, are ordinary automatic substations. Substation A is one of a hundred similar substations that terminate in a sub exchange. Each substation line may terminate at the sub exchange in a rotary line switch of the usual type, the line switch in which the line of substation A terminates being indicated by the reference character C. The line switch in which substation A'

terminates is also a rotary line switch and is indicated by the reference character C', Fig. 3. The line switches in the sub exchange have common access to a group of switching selector repeaters, one of which is shown in Fig. 2 and is indicated by the reference character D.

The switching selector repeater D is a vertical and rotary switch of the usual Strowger type so far as mechanical construction is concerned, having special relays and circuits added, however, that enable it to function as a repeater. In this case the selector functions of the switch D are those of a third selector for it operates on the third digit to pick out an idle connector, or a repeater, depending upon whether the call is for the local or adjacent sub exchange.

There is a secondary line switch such as the line switch indicated by the reference character C³, Fig. 1, associated with each switching selector repeater, whose function is to pick out an idle trunk line leading to the main exchange for the purpose of completing the call to main in case the call is to go there or to any other main office, or in fact anywhere except to the local sub exchange or the adjacent sub exchange. One of the trunk lines to the main exchange to which the secondary line switch C³ has access is the trunk line comprising conductors 138 and 139. These conductors extend to the main exchange and terminate there in the incoming first selector E.

The selector E, Fig. 3, is mechanically of the well known vertical and rotary type and has its bank contacts arranged in horizontal rows or levels. The selectors denoted by the dotted rectangles E' and E² may be assumed to be similar to the selector E.

The connector switch denoted by the reference character H is assumed to be of the well known vertical and rotary type and for that reason the circuit is shown only in part.

The bank contacts shown in Fig. 4 are accessible to the switching selector repeater shown in Fig. 2. The upper and lower contacts of the lower bank, as well as the lower contacts of the upper bank, are multiplied between switches in the usual manner. The upper contacts of the upper bank are not multiplied, and they, together with the relays shown at the right, are associated only with the switching selector repeater having access to this particular bank.

To complete the general description of the system it may be said that calls from a main exchange to a sub exchange may be completed by way of a group of trunks that terminate in incoming connectors at the sub exchange.

The foregoing paragraphs will serve to give a general understanding of the character of the apparatus and the system of trunking which is employed. The system

having been described in general, a detailed description will now be given of its operation, and for this purpose it will be assumed that the subscriber at substation A desires connection with a subscriber in the same sub exchange, whose telephone number is 91,467. 70

When the receiver is removed at the calling substation A a circuit is completed over the conductors 11 and 12 for the line relay 15 of the line switch C. Upon energizing, relay 15 closes a circuit at its armature 20 which includes the winding of the switching relay 14 and the stepping magnet 16 in series, and at its armature 21 connects test wiper 26 to the above circuit at a point midway between the said switching relay and the stepping magnet. The operation now depends upon whether the trunk line with which the line switch wipers are associated is busy or idle. If the trunk line is busy 85 there is a ground potential upon the test contact with which the test wiper 26 is in engagement, the switching relay 14 is short circuited and the stepping magnet 16, which 90 interrupts its own circuit, is operated in the manner of a buzzer to advance the switch wipers in search of an idle trunk line. We may assume, however, in the present case that when the call is initiated the trunk line upon which the wipers of the line switch are 95 standing is idle. Under these circumstances when the line relay 15 is energized the switching relay 14 is not short circuited and the stepping magnet 16 is not operated because of the high resistance of said switching relay. The latter relay, however, is energized, grounds the test wiper 26 at armature 18, and at armatures 17 and 19 disconnects the line conductors 11 and 12 from the winding of relay 15 and ground, respectively, and extends them by way of wipers 25 and 27, and bank contacts 28 and 30, conductors 31 and 33, armatures 54 and 58 and their resting contacts, normally closed contacts of the electro-polarized reversing relay 110 44 to the upper and lower windings of the line relay 35 of the switching selector repeater D. The line relay 35 immediately energizes and closes the circuit of release relay 36 at armature 57. Release relay 36, 115 upon energizing, closes at armature 61 a holding circuit extending from ground at armature 61, conductor 32, test contact 29, test wiper 26, armature 18 and its working contact, switching relay 14 and stepping 120 magnet 16 to battery. It is understood that this circuit is established before the slow acting line relay 15 has had time to deenergize. By means of a ground potential on test contact 29 and its multiples, this holding circuit serves to render the switching selector repeater D busy to other line switches, and the busy potential also extends by way of private normal 13 to multiple test contacts 125 in the banks of the connectors, thereby 130

65 66 67 68 69 70 71 72 73 74 75 76 77 78 79 80 81 82 83 84 85 86 87 88 89 90 91 92 93 94 95 96 97 98 99 100 101 102 103 104 105 106 107 108 109 110 111 112 113 114 115 116 117 118 119 120 121 122 123 124 125 126

guarding the line against intrusion in the usual manner. In the switching selector repeater D a branch of the holding circuit extends from grounded conductor 32 through the upper winding of electro-polarized relay 44 to battery. This winding is of high resistance and few turns, and, therefore, cannot operate the relay until it is assisted by current in the lower winding.

When the line relay 35 is energized a bridge is closed across the trunk line conductors which is effective in operating the line relay 119 of the secondary line switch C³. The circuit for relay 119 is as follows: from ground through relay 119, resting contact and armature 125, conductor 105, armature 93 and its working contact, eleventh rotary step cam spring 53, operated by cam 94 and resting contact of said spring, lower winding of electro-polarized relay 44, impedance 38, resting contact and armature 66, conductor 101, armature 122 and its resting contact, resistance R³, common conductor 146, armature 145 and its resting contact to battery. The line relay 119 will energize over this circuit, but the current that flows in the lower winding of relay 44 opposes that in its upper winding and consequently it does not energize. Upon the energization of release relay 36 a circuit was traceable from ground at armature 62, eleventh rotary step cam spring 49, operated by cam 94, and its resting contact, conductor 102, relay 18, and stepping magnet 117 to battery. With relay 119 energized, it is seen that test wiper 132 is connected to the above circuit at a point between the switching relay and the stepping magnet. These circuit conditions are substantially the same as those that were described in connection with the operation of line switch C, and it necessarily follows that the line switch C³ operates to select an idle trunk line to the main exchange. Assuming that the trunk line comprising conductors 138 and 139 is the first one found idle, when the test wiper 132 arrives at test contact 136 the rotary movement ceases, no ground being found by test wiper 132, and the switching relay 118 is energized. As a result the conductors 101 and 105 are disconnected from common battery conductor 146 and the winding of the line relay 119, respectively, and are extended by way of armatures 122 and 125 and their working contacts, armatures 129 and 126 and their working contacts, wipers 130 and 133, contacts 134 and 137, trunk conductors 138 and 139, armatures 168 and 171 and their resting contacts to the upper and lower windings, respectively, of the line relay 151 of the first selector E in the main exchange. There being a bridge across conductors 101 and 105, as already explained, the line relay 151 of the selector E energizes and operates the release relay 152 in the usual manner there-

by making the selector E ready for the usual vertical impulses.

Returning to a consideration of the line switch C³ it may be said that when relay 118 energized it broke the original energizing circuit of line relay 119, but when armature 124 operated it opened the test circuit and closed a locking circuit for the line relay 119 before the said relay had time to deenergize. The afore-mentioned circuit extends from the working contact and armature 124, through armature 127 and its working contact, and stepping magnet 117 to battery. Stepping magnet 117, being wound with few turns and having a stiff adjustment does not energize at this time. As a further result of the energization of switching relay 118, armature 121 closes a circuit that extends from grounded conductor 102 through relay 120 to battery. Relay 120 energizes and places ground on the test contact 136 and its multiples in the banks of other secondary switches, in order to make the selected trunk busy, and at armature 140 it closes a point in the circuit of relay 144. The function of relay 144 will be fully explained at a later time.

The calling line has been extended to the switching selector repeater D and a branch from the said switch has been extended by way of the secondary line switch C³ to the first selector E in the main exchange. The dial tone produced by the dial tone machine T, Fig. 3, is now audible to the calling subscriber, it being placed on the trunk by virtue of the lower winding of the line relay 151 of selector E. We may now assume that the calling subscriber dials the first digit 9 of the called number, as a result of which nine interruptions are produced in the circuit of line relay 35 of switch D. At each interruption, the line relay 35 deenergizes and sends an impulse of current through the vertical magnet 47 over the following circuit: from ground through armature 60 and its resting contact, armature 57 and its resting contact, armature 63 and its working contact, normally closed contacts controlled by armature 69, slow-acting relay 40, and vertical magnet 47 to battery. The slow-acting relay 40 is energized in series with the vertical magnet and retains its armature attracted during the vertical movement. The slow-acting relay 37 is energized in parallel with the slow-acting relay 40, and the vertical magnet, and it also retains its armature attracted during the vertical movement. Upon the first upward step of the shaft, the vertical off normal springs 51 and 52 come into contact with their working contacts. The operation of the off normal spring 52 closes the circuit of the vertical off normal relay 39 which energizes and at armature 69 transfers the impulsive circuit so that it passes through the working contact of arma-

ture 69 and said armature, armature 74 and its working contact, and over the previously traced circuit to the vertical magnet 47. The operation of the vertical magnet raises the shaft and wipers 251 to 254, inclusive, Fig. 4, nine steps to a position opposite the ninth level of bank contacts.

The deenergization of line relay 35 not only brings about the operation of the vertical magnet 47, but also produces interruptions in the bridge across conductors 101 and 105, at armature 93. As a result, the line relay 151 of the distant selector E is deenergized nine times and the wipers 172, 15 173, and 174 are raised opposite the ninth level of bank contacts. In brief, the line relay 35 functions in the same manner as the line relay of the well-known automatic repeater to repeat the impulses to the line relay of the selector E. As a result, the switch D and the selector E are operated practically simultaneously. It will be noted that while the impulses are being repeated, the relay 37 is energized, and at its armature 66 25 closes the bridge across conductors 101 and 105 by way of a more direct path that excludes relay 44 and impedance 38. This is the usual expedient made use of to obtain first-class switch control.

30 The selector E, after raising its wipers to the ninth level, proceeds in the usual manner to select an idle trunk, and it may be assumed that the trunk line leading to second selector E' is the one first found to be idle.

35 Returning to a consideration of the switching selector repeater D, it will be found that slow-acting relays 37 and 40 deenergize following the last vertical impulse. Relay 37, at armature 66, replaces the original bridge across conductors 101 and 105, while relay 40 transfers the impulsive circuit from its working contact to its resting contact. Springs 97 and 98 are so placed on the switch that they are now in an operated position, on account of the shaft having been raised opposite the critical level 9. It may be stated here that a critical level is a level corresponding to the first digit of a switching combination.

50 It is assumed that the calling subscriber now dials the second digit 1 of the desired number. In response to the interruption in the line thus produced, the line relay 35 is deenergized once and, as before, repeats this impulse to the trunk line comprising conductors 138 and 139 leading to the main exchange. In response to this repeated impulse, selector E' raises its wipers one step to a position opposite the first level of bank contacts and rotates them in search of an idle trunk line. It may be assumed that the trunk line leading to the selector E² is the first to be found idle.

55 At the same time that relay 35 of switch D repeats the impulse to the main exchange,

it operates the rotary magnet 46 over the following circuit: from ground over the previously described impulsive circuit to the armature 74 of relay 40 and thence through the resting contact of said armature, shaft controlled spring 97 and its working contact, resting contact and armature 99, rotary magnet 46 to battery. The rotary magnet receives one impulse over this circuit in multiple with slow relay 37 and, accordingly, steps the wipers 251-254, inclusive, into engagement with the first set of contacts in the ninth level. Relay 37 now deenergizes and completes a circuit for relay 43 as follows: from ground through the upper winding of relay 255, Fig. 4, bank contact 266, wiper 251, conductor 95, resting contact and armature 65, relay 43 to battery. Relay 43 will not energize at this time due to the high resistance of relay 255. The latter relay, upon energizing, closes a locking circuit for its lower winding by way of grounded release trunk conductor 32 and armature 267. A further result of the energization of relay 255 is the operation of armature 268, which removes ground from bank contact 269 and places direct ground upon bank contact 266, whereupon relay 43 will become energized. Relay 43, when energized over the above circuit, closes a circuit traceable as follows: from ground over the previously traced circuit for relay 43, to working contact and armature 86, working contact and armature 70, armature 79 and its resting contact, release magnet 48 to battery. Release magnet 48 accordingly energizes and restores the switch shaft and wipers to normal. In order that the circuit of release magnet 48 and relay 43 may be maintained after the wiper 251 leaves bank contact 266, the release magnet, upon energizing, attracts its armature and closes a locking circuit for itself and relay 43 as follows: from ground at the armature of release magnet 48, working contact and armature 70, and over previously traced circuit to the release magnet 48, a branch circuit extends by way of armature 86 and its working contact to relay 43. When the shaft reaches its normal position, it forces off normal spring 52 away from its working contact which opens the circuit of the off normal relay 39. Relay 39 deenergizes and at its armature 70 removes direct ground from the circuit of the release magnet 48 and, in so doing, it leaves the release magnet 48 and the lower winding of relay 42 connected in series over the following circuit: from ground at armature 84, lower winding of relay 42, armature 79 and its resting contact, and release magnet 48 to battery. Owing to the relatively high resistance of the lower winding of relay 42, the release magnet 48 deenergizes while the relay 42 energizes and at armature 82 locks

itself to grounded release trunk conductor 32 by means of its upper winding. This is accomplished by so adjusting the relay 42 that armature 82 makes contact with its 5 working contact before armature 79 breaks away from its resting contact. When the release magnet 48 deenergizes, it breaks the circuit of relay 43, which, accordingly, deenergizes and breaks the circuit of the 10 lower winding of relay 42. Relay 42, however, does not deenergize, because a locking circuit has been closed through its upper winding.

The effect of the calling of the second 15 digit has been to raise the wipers of the second selector E' in the main exchange to the first level, whereupon the connection was extended to the third selector E². In the 20 sub exchange the switch D rotated its wipers one step, and, upon its wiper 251 finding a grounded contact in the associated bank, operated the release magnet 48, thereby causing the shaft and wipers to be returned to normal.

25 It may now be assumed that the calling subscriber dials the third digit 4 of the called number and, as a result, four impulses are repeated to the third selector E² in the main exchange, which raises its wipers opposite the fourth level of bank contacts and rotates in search of an idle trunk line. It will be assumed that the trunk line terminating in bank contacts 197, 198, and 30 199 is the first to be found idle. Since this trunk line is reached by calling 914, it must necessarily give access to the sub exchange, accordingly, it leads to a repeater and from there to an incoming connector located in 35 the sub exchange.

40 At the same time that the switch D repeats the four impulses to the selector E², it operates its vertical magnet 47 in the same manner as it did when the first digit was called. In this case, the vertical magnet causes the wipers to be raised opposite the fourth level of bank contacts. The vertical off normal springs close and complete the circuit of off normal relay 39 which energizes as before. Upon energizing, it completes at armature 72 the following circuit: from ground at armature 62, armature 64 and its working contact, resting contact of eleventh rotary step cam spring 50, armature 72 and its working contact, resting contact and armature 85, working contact and armature 80, stepping relay 41 to battery. Relay 41 energizes over this circuit and at armature 76 establishes the following locking circuit for itself: from ground at armature 60, armature 76 and working contact, armature and resting contact of rotary magnet 46, and thence over previously traced circuit to relay 41. At the end of the vertical movement, the slow-acting relay 37 deenergizes and at armature 64 closes a circuit for rotary mag-

net 46 as follows: from ground at armature 62, armature 64 and its resting contact, armature 75 and its working contact, and rotary magnet 46 to battery. Rotary magnet 46, upon energizing, steps the wipers 251 to 70 75 254, inclusive, into engagement with the first set of contacts in the fourth level of their associated banks, and at the same time operates to break the locking circuit of stepping relay 41. Relay 41 accordingly deenergizes and at armature 75 breaks the circuit of rotary magnet 46, which, in turn, deenergizes. The operation now depends upon whether the first trunk is busy or idle. If the first trunk is busy, there is a ground on 80 the private conductor terminating in the test contact 265, completing a circuit extending from contact 265 through test wiper 252, conductor 96, armature 88 and its resting contact, armature 59 and its resting contact, 85 armature 81 and its working contact, resting contact and armature of rotary magnet 46, and over the previously traced circuit to relay 41. Relay 41 accordingly energizes and at armature 75 closes the previously 90 traced circuit for rotary magnet 41 which operates to step the wipers over to the next set of contacts. This cycle of operation is repeated until an idle trunk is reached. When an idle trunk is found, relay 45 energizes in series with the stepping relay 41 over the following circuit: from grounded conductor 32, switching relay 45, armature and resting contact of rotary magnet 46, and over the previously traced circuit through 95 relay 41 to battery. Relay 41, however, due to its relatively small number of turns, does not energize in series with relay 45. It will be assumed that the trunk line terminating 100 in the first set of contacts is idle, and when the wipers reach the first set of contacts, the test wiper 252 finds no ground, and the switching relay 45 is accordingly energized. Upon energizing, relay 45 connects test wiper 105 252 to conductor 32 by way of armature 59 and its working contact, and at armatures 54 and 58 disconnects the incoming line conductors from the upper and lower windings of line relay 35 and extends them by way 110 of conductors 91 and 92, wipers 253 and 254, bank contacts 256 and 257 to trunk line conductors 259 and 260, understood to extend to and terminate in the line relay of a local connector switch. The line and release relays of the connector are accordingly energized and the latter grounds the release trunk conductor 258. This ground extends back to conductor 32 and its multiples and by means of it relay 14 of the line switch C and relay 45 of switch D are maintained energized and thus hold the switches C and D in an operated position. It is understood that this holding circuit is established before the slow-acting release relay 36 has had 115 time to deenergize. The connection through 120 125 130

the main office is released by the deenergization of line relay 35 of switch D following the operation of the switching relay 45. The slow-acting relay 36 deenergizes soon after the deenergization of relay 35, and at armature 62 disconnects ground from holding conductor 102, thereby breaking the circuit of relays 118 and 120. Relay 118 immediately deenergizes and breaks the circuit of relay 119. Relays 119 and 120, being slow-acting, do not release immediately and the stepping magnet 117 is energized and steps the wiper of switch C³ into engagement with the next set of bank contacts. The object of stepping the wipers ahead one step upon releasing, is not only to secure a better distribution of the calls, but also to prevent the tying up of a call by a defective trunk line. Suppose the trunk line comprising conductors 138 and 139 is defective, in such a case a party might try repeatedly to get a main exchange number without success for on each attempt he might get the same defective trunk line. With the arrangement shown, however, the first attempt would be unsuccessful, if the connection was attempted by way of the defective trunk line, but when the calling party disconnected to try the number over again, he would get a new trunk line, and ultimate success would be assured, even if it should be necessary to try all of the available trunks.

The connection under consideration has now been extended to a local connector in the sub exchange, and the trunk line to the main exchange has been released and restored to common use. The calling subscriber may now dial the remaining digits 6 and 7 of the desired number, with the result that the local connector to which the call has been extended is operated to complete the connection to the desired called line. This part of the operation is old and need not be further considered.

A description will now be given of the operation of establishing a connection between substation A and a substation in the adjacent sub exchange, whose number will be assumed to be 76,367. When the subscriber at substation A removes his receiver, it may be assumed that the connection is extended to the switch D, and by way of the secondary line switch C³ to the first selector E, in the manner previously explained. When the dial is operated for the first digit 7 of the called number, the selector E operates to raise its wipers opposite the seventh level of bank contacts and to select an idle trunk line therein. It may be assumed that conductors 161, 162, and 163 represent the first idle trunk, and that they extend to a repeater (not shown) associated with a trunk line terminating in an incoming second selector in the 70,000 office. The dialling of the digit 7 also causes the switch D to raise

the wipers 251 to 254, inclusive, opposite the seventh level of bank contacts. The shaft controlled springs 97 are now in an operated position, as level 7 is a critical level.

When the calling subscriber dials the second digit 6 of the called number, the incoming second selector in the 70,000 office raises its wipers opposite the sixth level of bank contacts and selects an idle trunk line leading to a third selector in the same office. The dialling of the digit 6 also causes the switch D to rotate the wipers 251 to 254, inclusive, into engagement with the sixth contacts in their respective banks. When relay 37 deenergizes, following the last rotary impulse, a circuit is closed for relay 43 as follows: from ground through the upper winding of relay 270, Fig. 4, bank contact 271, wiper 251, conductor 95, resting contact and armature 65, relay 43 to battery. Relay 43 will not energize at this time due to the high resistance of relay 270. The latter relay, upon energizing, closes a locking circuit for its lower winding by way of grounded release trunk conductor 32 at armature 272. A further result of the energization of relay 270 is the operation of armature 273, which removes ground from bank contact 274 and places direct ground upon bank contact 271, whereupon relay 43 will become energized. A still further result of the energization of relay 270 is the placing of direct ground upon bank contact 266. Relay 43, upon energizing, brings about the release of the switch D in the manner previously explained.

When the calling subscriber dials the third digit 3 of the called number, the third selector in the 70,000 office raises its wiper opposite the third level of bank contacts, and rotates in search of an idle trunk line. Since the idle trunk line is reached by calling 763, it must necessarily give access to the adjacent sub exchange. Accordingly it leads to a repeater and from there to an incoming connector located in the adjacent sub exchange. The dialling of the digit 3 also causes the switch D to raise the wipers 251 to 254, inclusive, opposite the third level of bank contacts, whereupon it rotates in search of an idle trunk line, as before explained. It will be assumed that the trunk line terminating in the first set of contacts is idle, and that trunk conductors 275, 276, and 277 extend to a repeater associated with an incoming connector in the adjacent sub exchange. The releasing of the main office trunk and the completion of the connection is brought about in the manner previously explained, and need not be described again.

A description will now be given of the operation of establishing a connection between station A and a substation in the main exchange, whose number will be assumed to be 91,367. As previously explained, the switching selector repeater under discussion

switches on the combination 914 and the combination 763. It is to be noted that the first three digits of the number 91,367 are a combination formed out of the two switching combinations and, notwithstanding this fact, the switching selector repeater must not cut off the main exchange trunk when this number is called. When the subscriber at station A calls the number 91,367, it will be assumed that the switch D is the one connected with, and that the connection at the end of the second digit 1 is exactly the same as it was at the end of the second digit in the description of the establishment of a connection from station A to station 91,467. The condition above referred to is as follows: At the main exchange, the connection has been extended by way of selectors E and E' to the third selector E², while in the sub exchange the wipers of the switch D have been raised opposite the ninth level of bank contacts and rotated in one step. When the wiper 251 engaged bank contact 266, various circuits were closed which caused the switch D to restore its shaft to normal, while at the same time relays 42 and 255 were operated and locked up to release trunk ground. With these facts in mind, the result of calling of the third digit 3 will be readily appreciated. When the dial is operated in accordance with the digit 3, the line relay 35 of switch D repeats the impulses over the trunk conductors 138 and 139 to the third selector E² in the main exchange, which raises its wipers opposite the third level of bank contacts and rotates them to select an idle trunk line leading to a connector switch. It will be assumed that the trunk line leading to connector switch H is the first one found to be idle. The line and release relays 182 and 183 immediately energize and the latter grounds the release trunk conductor in the usual manner to hold the preceding switches in an operated position. In the sub exchange the switch D raises its wipers to the third level and rotates them into engagement with the first set of contacts in the level. It will be remembered that the normal operation of switch D is as follows: The rotary magnet 46 advances the wipers into engagement with the first set of bank contacts and opens the circuit of stepping relay 41, the latter relay then deenergizes and, in turn, opens the circuit of rotary magnet 46. When the rotary magnet deenergizes, switching relay 45 will energize in series with relay 41 if the trunk is idle, or, if the trunk is busy, relay 45 will be shunted out and relay 41 will again energize. In the case under discussion, wiper 251 will engage bank contact 274 at the instant that rotary magnet 46 opens the circuit of stepping relay 41, and a circuit will be closed from ground at spring 273 and its resting contact, bank contact

274, wiper 251, conductor 95, resting contact and spring 65, through relay 43 to battery. Relay 43 will energize over the above traced circuit before the rotary magnet 46 deenergizes following the deenergization of stepping relay 41. Relay 43, upon energizing, opens the circuit of relay 41 at armature 85, and as a result, switching relay 45 cannot operate, neither can further rotation take place. It is to be noted that wipers 253 and 254 are clear at the contacts of armatures 54 and 58, respectively, and that relay 43 clears the test wiper 252 at armature 88; therefore, the fact that switch D is standing on the first set of contacts will in no way interfere with the use of the associated trunk by other switching selector repeaters. When relay 43 energizes, it closes at armature 87 a multiple point in its circuit so that it will not be deenergized when relay 37 operates armature 65 in response to the next digit called.

It will be seen that as a result of the calling of the third digit 3, which finally determines that the call is going to the main exchange, the switch D raised its wipers opposite the third level of bank contacts and rotated them into engagement with the first set of contacts in that level, thus operating relay 43 which prevented the further operation of the calling device from causing any mechanical operation of switch D. The switch D, however, can still function as a repeater to repeat the impulses to the main exchange. In the main exchange, we have the selectors E, E' and E² operated and the connector extended to the connector H. The calling subscriber may now operate his calling device in accordance with the last two digits 6 and 7 of the called number and when he does so, the connector H lifts its wipers to the desired level and rotates them into engagement with contacts 192, 193, and 194, in which the desired line terminates. This part of the operation is old and need not be considered in detail. Only so much of the connector H is shown as is needed to make the present invention clear. When the called subscriber answers, the back bridge relay 181 energizes in the usual manner and serves to reverse the polarity of the trunk at armatures 184 and 185. As a result, the current flow in the lower winding of relay 44, switch D, is reversed, therefore, the said relay in turn energizes and reverses the polarity of the trunk conductors 31 and 33.

This operation has no function in the present disclosure, but on account of its being standard practice the circuits are shown in this way. After the connection is completed, the subscribers will hang up their receivers and the release will take place in the usual manner.

A description will now be given of the operation of establishing a connection between

substation A and substation 95,567. Since, the second digit of this number is not the same as the second digit of the numbers of lines terminating in either sub exchange, the second digit called will determine that the call cannot be intended for either sub exchange and, consequently, the switch D will not need to move its wipers after the second digit is called. It will be assumed that the subscriber at substation A has removed his receiver and has called the digit 9 and he has obtained connection with the same switches, or in other words, conditions are exactly the same in this case as they were at the end of the digit 9, when the call to station 91,467 was described. It will be remembered that the shaft of switch D has caused the operation of spring 97, and that the switch is ready to rotate under the control of the calling device. The selector E in the main exchange in response to the calling of the first digit 9, raised its wipers opposite the ninth level of bank contacts and rotated to pick out an idle trunk leading to the second selector E'. With the call thus extended, the subscriber at substation A operates his calling device for the second digit 5 of the desired number. The result in the main exchange is that the selector E' raises its wipers opposite the fifth level of bank contacts and rotates to pick out an idle trunk line leading to a third selector (not shown).

At the sub exchange the switch D rotates its wipers five steps into engagement with the fifth set of contacts in the ninth level. As soon as the slow-acting relay 37 deenergizes, the following circuit is completed: from ground through resistance R, Fig. 4, bank contact 263, wiper 251, conductor 95, resting contact and armature 65, and relay 43 to battery. Relay 43 energizes and locks itself at armature 87, thus becoming independent of armature 65, and at armature 86 closes a circuit for release magnet 48 as follows: from ground over the previously traced circuit for relay 43, working contact and armature 86, working contact and armature 70, armature 79 and its resting contact, and release magnet 48 to battery. Release magnet 48, having a winding of few turns and having also a stiff adjustment, does not energize at this time. A further result of the energization of relay 43 is the closing of a circuit through relay 42 which may be traced as follows: from ground at armature 84, lower winding of relay 42, armature 79 and its resting contact, and release magnet 48 to battery. At this time release magnet 48 is feeding battery through the lower winding of relay 42 in parallel with resistance R; due to its structure release magnet 48 does not energize at this time. Relay 42 energizes and just before armature 79 breaks away from its resting contact, armature 82 makes on its working contact, thereby lock-

ing relay 42 by means of its upper winding to the grounded release trunk conductor 32. Armature 79 opens the circuit to release magnet 48, while 99 opens the circuit of the rotary magnet to prevent further rotation of the switch in response to dial impulses.

The calling of the remaining digits 5, 6, and 7 produce no movement of the wipers of the switch D, the switch acting merely as a repeater to repeat the impulses to the main exchange where, by means of the switches not shown, the call is completed. After the termination of the conversation, the subscribers hang up their receivers and the release takes place in the usual manner.

A description will now be given of the operation of establishing a connection between substation A and any substation which is in an office other than the main office, or the local or adjacent sub exchange, for instance station 84,567. Since the first digit of this number is not the same as the first digit of the numbers of lines terminating in either sub exchange, the first digit called will determine that the call cannot be intended for either sub exchange and, consequently, the switch D will not need to move its wipers after the first digit is called. It will be assumed that the subscriber at substation A has removed his receiver and obtained connection with switch D.

When the calling subscriber operates his calling device for the first digit 8 of the desired number, the switch D operates in the usual manner to raise its wipers opposite the eighth level of bank contacts, while the selector E in the main exchange raises its wipers opposite the eighth level and rotates to pick out an idle trunk line leading to a repeater (not shown) and thence to an incoming second selector in the 80,000 office. Since, the eighth level in the bank of switch D is not a critical level, the shaft spring 97 is not operated at this time, and, consequently, the circuit of the rotary magnet is open at that point. This being the case, the switch D can function only as a repeater. When the subscriber at substation A operates his calling device for the remaining digits 4, 5, 6, and 7 of the called number, the switch D, acting as a repeater, repeats the impulses to the repeater in the main exchange which again repeats them to the switches in the 80,000 office. This part of the operation is old and need not be further considered.

The rather complex operations hereinbefore described may be summarized as follows: If the first digit dialed is a critical digit, that is, a digit corresponding to the local or adjacent sub-exchange, the switch D raises its wipers in response to the digit dialed, operates shaft springs 97 and 98, thus preparing for a dial controlled rotary movement.

If the first digit dialed is not a critical

digit, switch D raises its wipers in response to the digit dialled. The springs 97 and 98 are not operated, however, and, therefore, no dial controlled rotary movement can take place. The switch remains in the operated position and functions only as a repeater.

If the first digit dialled is a critical digit, followed by a second critical digit, that is, the second digit appearing in the switching combination of the sub exchange determined by the first digit called, switch D rotates in response to the second digit and releases. In doing so a relay is operated which removes ground from the guarding contact corresponding to the last digit of the switching combination of the sub exchange determined by the first digit called.

If the first digit dialled is a critical digit, followed by a second digit which is not critical, switch D rotates in response to the second digit, but the switch does not release. The switch remains in the operated position and functions only as a repeater.

If the first two digits dialled are critical digits, followed by a third critical digit, that is, a third digit appearing in the switching combination of the sub exchange determined by the first digit called, switch D raises its wipers in response to the third digit, cuts in on the selected level and seeks an idle trunk to a local connector or to a repeater as the case may be. At the same time the trunk to the main exchange is released.

If the first two digits dialled are critical digits, followed by a third digit which is not a critical digit, the switch D raises its wipers in response to the third digit and cuts in one step on the selected level, remaining in that position and functioning only as a repeater.

A special case is presented when the first digit of the switching combination is the same as the third digit, the additional equipment required is shown in connection with the second level of the banks shown in Fig. 4. In order that this feature may be made clear, it will be assumed that a third sub exchange may be reached from the banks of the switch D, should the combination 232 be called. The switch D, in response to the dialling of the digits 2 and 3, will cause the wiper 251 to engage bank contact 278, whereupon a circuit is closed for relay 43 over the following circuit: from ground at armature 279, upper winding of relay 280, bank contact 278, wiper 251 and over the previously traced circuit through relay 43 to battery. Relay 43 will not energize at this time owing to the high resistance of the upper winding of relay 280; the latter relay will energize, however, and close the circuit of relay 281 at armature 282. A further result of the energization of relay 280 is the operation of armature 283 which

places ground through the low resistance lower winding of relay 280 upon bank contact 278, whereupon relay 43 will energize and close the usual circuit through release magnet 48 and the lower winding of relay 42. The resistance of the lower winding of relay 280 is so low that it effectually shunts the lower winding of relay 42, therefore, the latter relay does not energize at this time. The release magnet 48, however, energizes in series with the lower winding of relay 280, and operates to provide a locking circuit for itself and relay 43, and furthermore causes the switch D to restore to normal. As previously explained, the lower winding of relay 42 energizes in series with the release magnet 48 when armature 70 removes direct ground from the circuit. Relay 42 locks up through its upper winding and prepares the switch for the next series of impulses.

Returning to a consideration of relay 280, it will be seen that, upon energizing, it closes a circuit through relay 281 at armature 282. Relay 281, upon energizing, forms a locking circuit for itself from grounded release trunk conductor 32 by way of armature 284, thus rendering it independent of the further operation of relay 280. A further result of the energization of relay 281 is the removal of ground from the resistance R^2 at armature 279, and the placing of ground upon bank contact 266 by way of armature 285. Relay 280 will remain operated until such time as release magnet 48 places direct ground upon the circuit at which time relay 280 deenergizes and clears bank contact 278.

It will be assumed that the switch D now responds to the dialling of the digit 2 by raising its wipers opposite the second level of bank contacts and, since relay 43 is now deenergized as previously explained and since there is no ground upon any of the bank contacts accessible to wiper 251, the switch D will automatically rotate in search of an idle trunk line leading to a repeater, the said repeater being associated with a trunk line terminating in an incoming connector located in the third sub exchange. The main office connection is released in the usual manner.

The introduction of the third sub exchange has still further complicated the operation, and for that reason reference is again made to Fig. 4. It will be remembered that the fourth level contains trunk lines, such as the trunk line represented by reference characters 258, 259, and 260, which lead to connectors in the local sub exchange. The third level contains trunk lines, such as the trunk line represented by reference characters 275, 276, and 277, which lead to repeaters, the said repeaters being associated with incoming connectors at the second sub

exchange. The second level contains trunk lines, such as the trunk line represented by reference characters 286, 287, and 288, which lead to repeaters, the said repeaters being associated with incoming connectors at the third sub exchange. The switching combination of the local sub exchange is 914, while the switching combination of the second sub exchange is 763, and that of the third exchange is 232.

When considering the first operation of the calling device, the critical digits comprise the first digit occurring in each of the switching combinations; in this particular case 9, 7, and 2. If the first digit called on switch D be other than 9, 7, or 2, the shaft will be raised but the shaft springs 97 and 98 will not be operated, and the switch will remain in the operated position and function only as a repeater. If the first digit called on switch D be either 9, 7, or 2, the shaft will be raised and the shaft springs 97 and 98 will be operated, thus preparing for a dial controlled rotary movement.

When considering the second operation of the calling device, the critical digit is the second digit occurring in the switching combination determined by the first digit. That is, the digit 1 is a critical digit only when it follows the digit 9, the digit 6 is a critical digit only when it follows the digit 7, while 3 is a critical digit only when it follows the digit 2. If a first critical digit is dialled, followed by a second digit which is not critical, for instance 92, 71, or 20, the switch D will rotate the wiper 251 into engagement with a bank contact grounded through a resistance, such as R or R², and the switch D will remain in the operated position and function only as a repeater. If a first critical digit is dialled, followed by a second critical digit, for instance 91, 76, or 23, the switch D will rotate the wiper 251 into engagement with a bank contact which becomes grounded, either directly or through a very low resistance, whereupon the switch D releases and in so doing, causes a relay, such as the relays 255, 270, or 280 to operate and remove ground from the first guarding bank contact in the level corresponding to the third digit in the switching combination determined by the first digit.

When considering the third operation of the calling device, the critical digit is the third digit occurring in the switching combination determined by the first digit. That is, the digit 4 is critical only when it follows the number 91. If two critical digits are dialled, followed by a digit which is not critical, for instance 917, 762, or 234, the switch D will raise its wipers opposite the desired level and automatically cuts in on the first set of contacts. Whereupon the wiper 251 engages a contact grounded directly or through a resistance such as R or R', in

either case, relay 43 of switch D will energize to prevent the operation of switching relay 45. The switch D will remain in the operated position and will function only as a repeater. From the foregoing, it will be seen that previous to the calling of the third critical digit, the first guarding contact in each level, except that level corresponding to the third digit in the switching combination determined by the first digit, must be grounded either directly or through a resistance such as R or R'. Since contact 266 is normally grounded through the high resistance upper winding of relay 255, means must be provided whereby this contact may be grounded to meet the requirement above referred to. Therefore the relay associated with the guarding contact corresponding to the second digit of each switching combination is provided with a pair of springs which are multiplied in such a way that contact 266 will be grounded when any one of the above mentioned relays are energized. It may be stated that the first guarding contact, in any level which may be reached by a critical digit followed by a non-critical digit, is grounded through a resistance such as the resistance R or R', rather than by direct ground. This prevents the release of the switch D, should the contact in question be reached at the end of the second digit, yet provides a circuit for relay 43 should the said contact be reached at the end of the third digit.

If two critical digits are dialled followed by a digit that is critical, for instance 914, 763, or 232, the switch D will raise its wipers opposite the desired level and automatically cut in on the first set of contacts, and, since there is no ground upon the guarding contact, the switch D rotates in search of an idle trunk leading to a local connector, or to a repeater, as the case may be. At the same time, the trunk to the main exchange is released.

It will be seen that the switching combinations are not limited to any particular combination of digits, and it will also be understood that additional levels may be wired for local or adjacent switching if so desired.

The foregoing part of the explanation will now be supplemented by a detailed consideration of some of the circuit refinements that have been incorporated in the circuit of switch D.

The switching selector repeater disclosed in the before mentioned patent was designed to supply dial tone to the calling subscriber as soon as a connection was extended thereto. The calling subscriber, therefore, received notification to proceed with the dialling before the associated secondary line switch had selected an idle main exchange trunk. This objectionable feature has been eliminated in the present disclosure.

by arranging the circuits in such a way that the dial tone will be received from the incoming first selector at the main exchange. If all the trunks to the main exchange are 5 busy it is evident that dial tone cannot be received from a first selector therein; yet it is necessary at this time to provide a dial tone, since there is a possibility that the contemplated call will be for a number located 10 in the local, or one of the adjacent, sub exchanges. An explanation will now be given of the operation of providing dial tone should all of the main exchange trunks be 15 busy when a call is originated in the sub exchange.

Upon referring to Fig. 1, it becomes evident that when all trunks to main, such as the trunk line comprising conductors 138 and 139 are busy, all relays, such as relays 120, 142, and 143, are energized and thus 20 complete a circuit extending from ground by way of the working contact of armature 140 and said armature, and the corresponding contacts and armatures on relays 142 and 143 to battery through relay 144. Relay 144, upon energizing, removes battery from common conductor 146. In case all of the trunks to main are busy when the subscriber at substation A makes a call by way 25 of switch D the energization of line relay 35 closes a bridge across conductors 101 and 105, but, since battery is removed from common conductor 146, the relay 119 of switch E cannot energize. Switching relay 118, 30 however, energizes as before, due to the closure of its circuit by relay 36 at armature 62. At this time it is to be noted that the circuit extending to wipers 130 and 133 is open at armatures 129 and 126, respectively, 35 of relay 119; and that local dial tone is now audible at substation A, it being delivered over the following circuit: from ground through the secondary winding of dial tone machine T, resting contact and armature 77, 40 resting contact and armature 71, resting contact and shaft spring 98, conductor 104, armature 128 and resting contact, working contact and armature 122, conductor 101, armature 66 and resting contact, 45 upper talking condenser, resting contact and armature 54 to line conductor 31; the return circuit being completed through the lower winding of line relay 35. The calling subscriber now operates his calling device for the first digit of the desired number. The dial tone is cut off at armature 71 when 50 relay 39 energizes in response to the operation of off normal spring 52. If the number called is such that switch D releases at the end of the second digit, the dial tone is 55 not again placed on the line for, under the condition just stated, its circuit will be open at armature 77 of relay 42.

While not a part of the present invention, 60 the method of giving the busy tone to the

calling subscriber when all main office trunks are busy will now be described. Returning to the circuit arrangement outlined in the preceding paragraph, it may be assumed that the calling subscriber has heard the dial tone 70 and now operates the dial for the first digit of the desired number. At the first vertical step, relay 39 will energize and operate to place the busy tone from machine B upon line conductor 31 over the following circuit: 75 from battery through secondary winding and condenser of busy machine B, working contact and armature 71, resting contact and shaft spring 98 and over the previously traced circuit to line conductor 31. If the 80 first digit dialled be other than a critical digit, the shaft spring 98 will remain in an unoperated position, and the calling subscriber will receive the busy tone as soon as his dial returns to normal. If the first 85 digit dialled is a critical digit, there is a possibility that the call is for a number in the local, or one of the adjacent, sub exchanges and, under the condition just stated, the busy tone will not be audible because 90 shaft spring 98 is in an operated position.

If the first digit dialled is a critical digit, followed by a second digit which is not critical, relays 43 and 42 will energize. The open contact at shaft spring 98 will be shunted by the closed contact of armature 78 of relay 42 and the calling subscriber will receive the busy tone as soon as his dial returns to normal. If the first digit dialled is a critical digit, followed by a second critical digit, 100 there is a possibility that the call is for a number in the local, or one of the adjacent, sub exchanges and, under the condition just stated, the busy tone will not be audible owing to the open circuit at armature 71 of 105 relay 39, it being remembered that switch D released to normal because of the dialing of two critical digits.

If the two first digits dialled are critical digits, followed by a third digit which is not critical, relay 39 will again energize and, under the condition just stated, the calling subscriber will receive the busy tone as soon as his calling device returns to normal. If the two first digits dialled are critical, followed by a third critical digit, the switch D will select a trunk to an idle connector or repeater, the switching relay 45 operating to cut off the main exchange trunk and, under the condition just stated, the busy tone 115 will not be audible owing to the open circuit at armature 54 of relay 45.

In the drawing the springs 49, 50, and 53 are shown divided for convenience only, actually they are grouped together and controlled by a single cam. The purpose of these springs is to give the calling subscriber a busy signal when he calls a number in the local, or in an adjacent, sub exchange and finds all the trunks busy. Under the condi- 120 125 130

tion above set forth the trunk to the main exchange is also released. When the switch D is used in calling a number, the first three figures of which constitute a switching combination, the wipers are automatically rotated in search of an idle trunk line leading to a connector or to a repeater. If an idle trunk line is not found the wipers are rotated until they pass off the last set of contacts in that level and when they do so, the shaft cam 94 operates the springs 49, 50, and 53. At spring 50, the circuit of switching relay 45 is broken to prevent the said relay from energizing and opening the circuit of line relay 35. Spring 53 opens the bridge across conductors 101 and 105, thereby releasing the connection to main, while spring 49 opens the holding circuit of switch C, thus freeing the main exchange trunk. Spring 53 in addition to opening the bridge across conductors 101 and 104, also closes a circuit from busy machine B to the lower talking condenser and thence back to the calling subscriber to inform him that he cannot obtain the desired connection.

The features of the invention having been described and ascertained, what is considered to be new and desired to have protected by Letters Patent will be pointed out in the appended claims.

I claim:

1. In a telephone system, two main exchanges each having a branch exchange subsidiary thereto, automatic switches in said exchanges, a switching selector repeater in one of said branch exchanges accessible to a calling subscriber, means in said selector repeater responsive to the first three digits in the called number for repeating impulses over a trunk line to the associated main exchange to operate a series of said switches, local connectors accessible to said selector repeater, trunk lines extending to the other branch exchange also accessible to said selector repeater, means for operating said selector repeater in its primary movement responsive to the first digit in the called number, means for operating said selector repeater in its secondary movement responsive to the second digit in the called number, means for then automatically releasing said selector repeater, means for reoperating said selector repeater in its primary movement responsive to the third digit in the number, means for automatically operating said selector repeater in its secondary movement to select an idle local connector, or an idle trunk line to the other branch exchange, depending on the number called, means for switching the calling line through to the selected connector or trunk line, and means for releasing the switches which were operated over the main exchange trunk line.

2. In a telephone system, main and branch exchanges, a switching selector re-

peater in one of said branch exchanges, local trunk lines accessible to said switching selector repeater, trunk lines extending to another branch accessible to said selector repeater, trunk lines to a main exchange, a line switch individual to said selector repeater having access to said main exchange trunk lines, means for operating said line switch to select a main exchange trunk line when said selector repeater is taken for use, means in said selector repeater for repeating the first three digits in the number called over the selected main exchange trunk line, said selector repeater having wipers operated responsive to such digits also, means effective in case three digits are called which identify the called line as being in the local branch or in said other branch for causing said wipers to select and connect with an idle local or branch trunk, as the case may be, and means for releasing the partially established connection in the main exchange.

3. In a telephone system, a main exchange and a branch exchange, main exchange trunk lines connecting said exchanges, a second exchange accessible to subscribers in said branch exchange via said trunk lines, a switching selector repeater in said branch exchange having means for seizing a main-exchange trunk line and for repeating the digits in called numbers over such trunk line, local trunk lines and direct trunk lines to said second exchange accessible to the wipers of said selector repeater, and means for operating the said selector repeater wipers to select one of said local trunk lines or one of said second exchange trunk lines, as the case may be, and release the selected main exchange trunk line, whenever such digits are called as determine that the called line is either a local line or a line in said second exchange.

4. In a telephone system, a main exchange and a plurality of branch exchanges, a switching selector repeater in one of said branch exchanges for extending local or outgoing calls, means in said selector repeater for preliminarily routing all calls via the main exchange, means in said selector repeater for switching local calls or calls to another branch exchange over routes bypassing the main exchange when digit combinations are called which exclude the main exchange, and means for preventing false switching operations due to the calling of digit combinations made up of one or more digits in each of two switching digit combinations.

5. In a telephone system, a main exchange and a plurality of branch exchanges, a switching selector repeater in one of said branch exchanges for extending local or outgoing calls, means in said selector repeater for preliminarily routing all calls via the

- main exchange, means in said selector repeater for switching local calls or calls to another branch exchange over routes bypassing the main exchange when digit combinations are called which exclude the main exchange, and means for preventing a false switching operation in case all but one of the digits in a certain switching combination are called followed by the final digit 10 in another switching combination.
6. In a telephone system, a main exchange and a plurality of branch exchanges, a switching selector repeater in one of said branch exchanges for extending local or outgoing calls, means in said selector repeater for preliminarily routing all calls via the main exchange, means in said selector repeater for switching local calls or calls to another branch exchange over routes bypassing the main exchange when digit combinations are called which exclude the main exchange, and means for preventing false switching operations due to the calling of digit combinations made up of one or more 20 digits in each of two switching digit combinations, said means comprising relays individual to said selector repeater, there being a relay for each switching combination, and circuit connections from said relays to the 30 bank contacts in said selector repeater.
7. In a telephone system, a main exchange and a branch exchange, a switching selector repeater in the branch exchange for handling all originating calls, means in said selector repeater for preliminarily routing all calls via the main exchange, means in said selector repeater for switching a call from the main exchange to the branch exchange as soon as sufficient digits are called to determine the destination of the call, means for transmitting a "dial tone" to a calling branch subscriber from the main exchange provided a main exchange trunk line is available, said tone informing the subscriber 40 that he can proceed to call the desired number, and means for giving the calling subscriber a "dial tone" from the branch exchange in case all the main exchange trunk lines are busy.
- 50 8. In a telephone system, a first office and a second office, trunk lines between said offices, other trunk lines, means for extending a connection from said first office to said second office over one of said inter-office trunk lines, a register, means responsive to the calling of a portion of the desired number for operating said register to record such portion and for transmitting corresponding impulses over the trunk line to the second office, a plurality of relays, means operative in accordance with the setting of said register for operating any one of said relays to record such setting and for releasing said 55 60 65 70 75 80 85 90 95 100 105 110 115 120
- register, said operating means being again effective for operating said register to record another digit in the called number, and means controlled in accordance with the operated relay and in accordance with the new position of said register for severing the connection to the second office and for extending the connection to one of said other trunk lines.
9. In a telephone system, a first office and a second office, trunk lines between said offices, two other groups of trunk lines, means for extending a connection from said first office to said second office over one of said inter-office trunk lines, a register individual to said connection, said register having two critical positions, two relays assigned to said critical positions, respectively, means responsive to the calling of a portion of a desired number corresponding to either critical position for setting said register into the critical position corresponding to such called portion and for transmitting corresponding impulses over the trunk line to the second office, means responsive to the setting of the register for operating the relay associated with the selected critical position and for releasing said register, two switching positions for said register normally ineffective corresponding, respectively, to said other groups of trunk lines, and associated with said critical positions, respectively, means controlled by the operated relay for rendering the associated switching position effective, said operating means being again effective to operate said register to record another digit, and means effective only in case such other digit corresponds to the last named switching position for severing the connection to the second office and for extending the connection to an idle trunk line in the one of said other groups of trunk lines which corresponds to the last named switching position.
10. In a telephone system, two main exchanges, each characterized by a separate and distinct block of telephone numbers, two branch exchanges associated with said main exchanges, respectively, each branch having assigned to it a portion of the numbers allotted to its associated main exchange, a switching selector repeater in one of said branch exchanges for extending local or outgoing calls, means in said selector repeater for preliminarily routing all calls via the associated main exchange, and means in said selector repeater for switching local calls or calls to the other branch over routes bypassing the main exchanges.
- In witness whereof, I hereunto subscribe my name this 30th day of January, A. D., 1923.

ARTHUR J. RAY.
